UNITED STATES PATENT OFFICE.

DANIEL N. JONES, OF JOHNSTOWN, PENNSYLVANIA.

HOT-BLAST STOVE.

SPECIFICATION forming part of Letters Patent No. 291,518, dated January 8, 1884.

Application filed June 29, 1881. (No model.)

To all whom it may concern:

Be it known that I, DANIEL N. JONES, of Johnstown, county of Cambria, State of Pennsylvania, have invented or discovered a new and useful Improvement in Hot-Blast Ovens; and I do hereby declare the following to be a full, clear, concise, and exact description thereof, reference being had to the accompanying drawings, making a part of this specification, 10 in which—like letters indicating like parts—

Figure 1, Sheet 1, is a vertical sectional elevation of one of the chambers of my improved oven, in the plane of the line $x\ x$, Fig. 2. Fig. 2 is a horizontal sectional view, partly in the 15 plane of the line $x'\ x'$; partly in the plane of the line $x^2\ x^2$, and partly in the plane of the line $x^3\ x^3$, of Fig. 1. Fig. 3, Sheet 2, is a sectional view of the valve and valve-boxes (to an enlarged scale) which I employ, as presently to be described, said section being taken 20 in the plane of the line $y\ y$ of Fig. 5. Fig. 4 is a like view of the same in the plane of the line $y'\ y'$, Fig. 5; and Fig. 5 is an end view of the valve-boxes, looking at the flat face of the 25 valve as seen at the open end.

My present invention relates to certain improvements in the construction of hot-blast ovens, wherein a more uniform action of the heating agencies employed is secured, and the 30 destruction of valves by the intense heat employed is more perfectly guarded against, while at the same time other minor details of improved construction facilitate the operations involved.

The regenerator principle of heating is employed, under which the ovens are built and used in pairs; but as each oven of a pair is practically a duplicate of the other, I have deemed it necessary in the drawings to show 35 only one of a pair. These ovens are made of cylindrical form, with an outer casing, A, of sheet or plate iron or steel, inside which is built the fire-brick lining A', of suitable thickness, but with an interposed layer or filling of 40 mineral wool, a, or other suitable packing having low heat-conducting properties. At suitable intervals in the height of this part of the oven projecting brick courses a' are laid, so as to support such filling. The inside of the vertical part of the oven is divided by tubular 45 shaft A², built of fire-brick, or, along with the lining A', of other suitable refractory mate-

rial capable of withstanding a high heat, so as to divide the same into two chambers, B B', the inner one, B, being the combustion-chamber, and the outer one, which is of annular form, being the regenerator-chamber. The oven thus formed is built on any suitable foundation, D, in which foundation are the pipes, ports, and conduits required for the work to 55 be done. A main conduit, D', is provided for the inflow of gas and for the outgoing hot blast, the gas being introduced through a branch, D², from the blast-furnaces, waste-gas pipe, or from any suitable gas producer or 60 purifier, and the hot blast going out by the branch D³ to the tuyere or place of use.

One feature of my present invention relates to the valves and water-boxes employed in these branch pipes D² D³, as well as in the chimney- 70 pipes, as will presently be described.

The conduit D' opens into the chamber B at its lower end, and the air necessary for effecting the combustion of the gas is introduced through one or more air-doors, d, into an air-chamber, d', from which one or more ports, d², open into the lower end of the combustion-chamber B. These ports d² may be of any desired number and size with reference to supplying air to the ingoing gas in proper amount 80 and properly subdivided for effecting the combustion of the gas during its passage up the chamber B. When the direction of the current is reversed for heating the blast, these air-supply passages are to be closed in any suitable way, as by doors or valves.

The chamber B' is to be filled with open brick-work, supported on arches r, so as to leave beneath such arches an annular flue, R, which opens, as at R', to the flue R², which 90 leads to the chimney. With this flue R² a cold-blast pipe, P, makes a junction outside the oven, and a valve, v, of suitable construction, is arranged therein, so as to be closed while the brick-work in chamber B' is being 95 heated, and to be opened when the blast is to be heated. A hollow water-supplied butterfly-valve, v', such as is hereinafter described, is to be arranged in the flue R², outside the junction-point of pipe P, so as to be closed 100 when the blast is being heated and opened when the brick-work of chamber B' is being heated. Cleaning-flues R³, leading to the dust-pit R⁴, may be added at pleasure, with doors

or valves for the usual purposes. Like clearing-flues may be added at other points, as desired or found necessary.

The action of the gas and air in heating and 5 in being heated will be readily understood by those skilled in the art without further description.

The first important feature of the present invention relates to the height of the inclosing-wall A² of the chamber B relative to the oven-top, whereby an annular throat, B², will be formed of such area relative to the area in horizontal cross-section of the chamber B that the gases, heat, &c., coming up and going 10 over, will be uniformly distributed all around the upper end of the wall A² and pass down through the brick-work in all parts of the chamber B'. The throat B² thus operates as 15 a kind of choke or throttle to the flow of gas, &c., so that instead of allowing it or the bulk of it to follow the shortest line to the exit-flue, which would be in the line of the arrow w, the throat on that side being too small for such purpose, the narrowness of the throat will render 20 it necessary for the gas, heat, &c., in order that the whole of it may get over, to pass over at all, or substantially at all, points in the throat, as indicated by the other arrows. In this way I insure the distribution of the heat 25 to all, or substantially all, parts of the brick-work filling, so as to take up and utilize the maximum amount of heat, and by uniformity of expansion and contraction increase correspondingly the durability of the oven; and as 30 regards the reverse currents or the heating of the air for the hot blast, the same elements of utility will be secured. The air forced up through the heated brick-work in the chamber B', instead of passing up chiefly on one 35 side, following the shortest line from its entrance to the adjacent side of the throat B², will be choked or throttled at that point, so as to be diffused throughout the heated brick-work in B', and be caused to pass over through 40 the throat B² at all, or substantially all, points. 45

Another feature of improvement relates to the valve and valve-boxes employed in the gas-inlet pipe D², the outgoing hot-blast pipe D³, and in the flue R², leading to the chimney. 50 Such valves are shown at c v', Figs. 1 and 2, and the boxes at c' c²; but, for greater clearness of illustration, I have shown in Figs. 3 to 5 the devices referred to on an enlarged scale. In the line of pipe communication—say in the pipe D²—I arrange a butterfly-valve, e, suitably shaped around its periphery for seating neatly on the boxes, as illustrated. On account of the intense heat to which, in this use of it, it is subjected, I cast it hollow, as shown 55 at e, and on a hollow stem, e', and at the ends of the stem make suitable connections for the supply and discharge of water to the inside of the valve, so as to prevent its destruction by heat. In order that it may seat tightly, it is 60 important that a metallic seat be provided, since a brick valve-seat will soon wear or be cut away; also, to get a tight seat, the valve, 65

when closed or seated, should not stand directly across the pipe at right angles to its axis, and the metallic seats, which thus are 70 not in the same transverse plane at right angles to the axis of the pipe, must, in order to avoid their destruction by heat, be water-lined or have water-backs; hence I make for each valve two annular water-boxes, c' c², and 75 pass the valve-stem through suitable seats made in their abutting or adjacent faces. The inner wall, n, of the water-box c' gives a valve-seat to one-half of the valve, and such inner wall may follow the curvature of periphery of 80 the seated valve to a point—say n'—at or past the valve-center, on both sides, and through the rest of its annular length it may be made narrower and be lined with fire-brick, n². The other water-box, c², furnishes a valve-seat for 85 the other half of the valve, and it has the same construction, except that the broad part of the box, the inner wall, n⁴, of which constitutes the valve-seat, extends around the other half or wing of the valve to a point—say at 90 n³—at or past the valve-center on both sides, and through the rest of its annular length may be narrowed and lined with fire-brick, n⁵, as 95 previously described. In this way I get good valve-seats properly protected, and with a minimum amount of area exposed to the peculiar action which variations of temperature have on cast-iron boxes. The usual water-pipe connections are of course to be added.

The filling in of brick-work in the chambers 100 B' may be of any desired style or pattern, that represented in Fig. 2 being preferred. The radial ribs r² of this filling are built up on the radial arches which are over the flue R, and the curved ribs r', in any desired number, follow substantially the form shown. These 105 are so built as to leave openings of the desired size. The central curved ribs are represented at r' in Fig. 1; but, as already stated, other forms or construction of filling may be employed, and in this respect I do not impose any limits on the features of invention herein claimed.

In constructing the oven described with reference to the useful result set forth, the area of 115 throat B² relative to the supply capacity of the chamber B may be varied somewhat, and hence I do not desire to limit myself to exact mathematical proportions; but in a general way it may be stated that the throat-area 120 should not materially exceed the supply or receiving capacity of the chamber B, and for the best results should, by preference, be somewhat less, the laws regulating the flow of air and gases under pressure being also taken into 125 consideration.

I am aware that hollow water-supply butterfly-valves seating against water-boxes, each having a metallic face extending around its entire periphery, are not new, and the same are 130 hereby disclaimed.

I claim herein as my invention—

1. In a cylindrical hot-blast oven having a central combustion-chamber, B, and a sur-

rounding regenerator-chamber, B', separated by a dividing-wall, A², the said wall A² extending up into proximity to the oven top or cover, and forming a throat, B², of about the same or less area than the combustion-chamber, whereby the flow or passage of the air or gas over the wall A² with practical uniformity on all sides is assured, substantially as set forth.

5 2. The water-boxes c' c², having each a metallic water-backed face extending half or a little more than half way around its annular

length and lined through the rest of its annular length, in combination with a hollow water-supplied butterfly-valve, substantially as set forth.

15 In testimony whereof I have hereunto set my hand.

DANIEL N. JONES.
